UNITED STATES PATENT OFFICE.

CLARENCE LEMUEL SAMUEL, OF PRYOR, OKLAHOMA.

AX-DISPLAY STAND.

1,132,392.

Specification of Letters Patent. Patented Mar. 16, 1915.

Application filed November 28, 1913. Serial No. 803,497.

To all whom it may concern:

Be it known that I, CLARENCE L. SAMUEL, a citizen of the United States, and a resident of Pryor, in the county of Mayes and State 5 of Oklahoma, have invented a new and Improved Ax-Display Stand, of which the following is a full, clear, and exact description.

This invention relates to display stands adapted especially for the display of axes, 10 ax handles and heads and other articles.

The general objects of the invention are to improve and simplify the construction of exhibiting stands, racks or the like so as to be comparatively inexpensive to manufacture, take up a minimum of floor space while having a large storing capacity, and at the 15 same time holding the axes in such a manner as to effectively display them.

Another object of the invention is the 20 provision of a display stand made in a plurality of sections, a main or central section serving to hold rows of handled axes or heads, a side or overhanging section carried by the main section and serving to hold ax 25 handles and unhandled heads, and another side section carried by the main section which serves to hold any desired articles, such as scythe blades.

Another object of the invention is to so 30 construct the rack or stand that it will hold a plurality of rows of axes which are effectively maintained in spaced relation, the means for holding each row of axes consisting of two horizontal bars for supporting 35 the heads of the axes and grip portions of the handles respectively, and a notched bit-engaging bar or spacing element into the notches of which the bits or blades of the axes engage, whereby the axes are held 40 spaced apart.

With such objects in view, and others which will appear as the description proceeds, the invention comprises various novel features of construction and arrangement of 45 parts such as will be set forth with particularity in the following description and claims appended hereto.

In the accompanying drawings, which 50 illustrate one embodiment of the invention, and wherein similar characters of reference indicate corresponding parts in all the views, Figure 1 is a perspective view of the combination stand or rack; Fig. 2 is a vertical section thereof showing rows of axes positioned thereon; Fig. 3 is an end view of a side rack or extension of the stand for hold- 55 ing the handles and ax heads; Fig. 4 is a vertical section of this side extension with ax handles positioned therein; Fig. 5 is an end view of the means for supporting scythe 60 blades; and Fig. 6 is a detail sectional view showing the manner of supporting the notched blade-receiving bars.

Referring to the drawing, a stand is shown as constructed of pipe stock and couplings so as to make a durable and substantial structure at a minimum of labor and expense, but it is to be understood that other material may be employed in the construction of the stand. The stand comprises 70 front standards A and A' and rear standards B and B', each of which is made of sections 1 of pipe united by couplings 2. The front standards are connected together by horizontal bars 3 which are united to 75 the standards by the couplings 2. Between the rear standards B and B' are horizontally disposed wooden bars 4 which are fastened by clips 5 to the couplings 2 of the rear standards, said clips being engaged 80 with bottom beads or flanges 6 of the couplings, as clearly shown in Fig. 6, so that the bars will not slip downwardly on the standards. Besides connecting the standards together these bars 4 serve to hold the 85 axes in the rack or stand in spaced relation, since the upper edges of these bars 4 are provided with spaced recesses or notches 7 to receive the bits or blades of the axes. In front of each bar 4 is a rest or support 90 disposed horizontally and consisting each of a section of pipe or rod. The ends of these supports 8 are connected with couplings 9 which are in turn connected by sections of pipe 10 with the couplings 2 of 95 the rear standards. Certain of the couplings 9 are united by sections of pipe 11 with the couplings 2 of the front standards so that the parts 9, 10 and 11, constitute means for uniting corresponding front and rear 100 standards together, so as to form a rigid structure. The upper sections of the front standards A and A' are curved upwardly and rearwardly and are united with the upper ends of the rear standards. In the present embodiment there are four notched blade-receiving bars 4, but any desired number may be employed. Coöperating with the lowest bar 4 is a front handle-supporting rod 3^a which is connected to the front stand- 110

ards by hangers 3^b which are fastened to the lowest couplings 2 of the front stand-

ards. In use, the axes are placed on the stand as shown in Fig. 2. The grip ends of the handles rest on top of the horizontal supports 3 and 3^a while the heads of the axes rest on the rear supports 8, the blades or bits of the axes extending into the notches 7 of the bars 4. In order that the dimension of the stand from front to rear may be reduced to a minimum the supports 3 are mounted considerably lower than the corresponding supports 8 for the rows of axes, and consequently the handles of the axes will be inclined downwardly from the rear to the front of the stand. The rows of axes are spaced vertically far enough apart to enable the axes to be taken from the stand with facility. As the grip ends of the handles are foremost any ax can be grasped and removed from the stand. When the stand is used against the wall the axes are accessible only from the front, but when the stand is placed nearer toward the center of the floor the axes are accessible from the rear, since both the front and rear of the stand are open. At the rear of the stand there is a top extension consisting of upwardly-extending members 12 fastened to the rear standards and a horizontal connecting member 13, on which latter is suspended a sign board 14 which can contain any suitable advertising matter.

The stand is provided with a lateral extension or rack section C which is made of pipe stock and couplings, this rack section being used for the purpose of holding ax handles and ax heads. The section C is a skeleton rectangular structure consisting of upper horizontal rods or bars 15 and 16 secured to couplings in the front and rear standards A and B, and lower front and rear bars 15^a and 16^a secured to couplings 2 in the said standards. The members 15 and 15^a are connected by vertical member 17, while the members 16 and 16^a are connected by a vertical member 18, couplings 19 being employed to unite the parts. Between the upper set of couplings 19 is a connecting member 20 extending from the front to the rear, and a corresponding member 21 unites the lower couplings 19. Between the members 15 and 16 are horizontal bars 22 which are arranged close enough together that between every pair of adjacent bars 22 ax handles can be placed and suspended by their grip ends, Fig. 4, since these ends are the thickest part of the ax handle. The head ends b of the handles extend downwardly through the bottom of the handle rack C, which bottom 60 is open. By suspending the handles in this manner there is no liability of their becoming twisted or warped, as is common in the case with the old methods of storing away handles. Obviously a large number of handles can be held between each pair of bars

22, so that the handle rack C, as shown, will have a large capacity. At the front, rear and sides of the rack C, are ax head supports or holders comprising vertical members 23 fastened to the top and bottom 70 of the rack C, and on these members 23 are laterally-extending fingers or cross members 24 on which single or double bit ax heads c, as shown in Fig. 3, are supported, the eyes of the ax heads receiving the horizontal supporting fingers 24. 75

At the opposite side of the stand from the handle rack C is a rack D used for the purpose of supporting rows of scythe blades. For supporting each row of blades an extension 8^a projects from each coupling 9, and a notched wooden strip or support 25 is mounted on the front standard A'. The hook or inner ends d of the scythe blade e are engaged over the extensions or members 8^a, to be supported thereby, as shown in Fig. 5, while the tip portions of the blades are supported by the notched strips 25. These strips 25, which serve to keep the blades spaced apart, are fastened by means of clips 90 26 to laterally-extending arms 27 fastened to the couplings 2 of the front standard A' and to the hanger 3^b. The edges of the blades are turned downwardly so that there is no danger of a person becoming cut by 95 accidental contact with the blades.

From the foregoing description taken in connection with the accompanying drawings, the advantages of the construction and method of operation will be readily understood by those skilled in the art to which the invention appertains, and while I have described the principle of operation, together with the device which I now consider to be the best embodiment thereof, I desire 100 to have it understood that the device shown is merely illustrative and that such changes may be made when desired as are within the scope of the appended claims. 105

Having thus described my invention, I 110 claim as new and desire to secure by Letters Patent:

1. A display stand comprising front and rear standards at each end of the stand, and each standard consisting of pipe sections 115 united by couplings, transverse members connected with the couplings of front and rear standards, longitudinal members connected with the couplings of the front standard, horizontal longitudinal members connected with the transverse members and disposed respectively above the corresponding front longitudinal members, and notched horizontal bars disposed adjacent the last-mentioned members and fastened to the couplings of the rear standard. 120

2. A display stand comprising front and rear standards at each end of the stand, and each standard consisting of pipe sections 125 united by couplings, transverse members 130

connected with the couplings of front and rear standards, longitudinal members connected with the couplings of the front standard, horizontal longitudinal members connected with the transverse members and disposed respectively above the corresponding front longitudinal members, notched horizontal bars disposed adjacent the horizontal longitudinal members and fastened to the 5 couplings of the rear standard, outwardly-extending article-holding members connected with the couplings of the front standards, notched bars on such outwardly-extending members, and additional outwardly-extending members disposed parallel with the last-mentioned notched bars and connected with the transverse members of the adjacent end of the stand.

3. A stand for displaying axes, comprising

ing rear standards made of sections of pipe 20 and couplings, notched bars extending between the standards, clips on the bars and engaged with the couplings for supporting the bars, bars attached to the standards and disposed in front of the notched bars for 25 supporting the heads of axes with the blades of the axes disposed in the notches of the bars, front standards, and bars extending between and connected with the front standards for supporting the handles of the axes. 30

In testimony whereof I have signed my name to this specification in the presence of two subscribing witnesses.

CLARENCE LEMUEL SAMUEL.
